US00D621933S

(12) **United States Design Patent**
Kupferschmid

(10) **Patent No.:** **US D621,933 S**
(45) **Date of Patent:** **** Aug. 17, 2010**

(54) **MEDICAL INSTRUMENT**

(75) Inventor: **Alexander Kupferschmid,**
Emmingen-Liptingen (DE)

(73) Assignee: **Karl Storz GmbH & Co. KG (DE)**

(**) Term: **14 Years**

(21) Appl. No.: **29/344,099**

(22) Filed: **Sep. 23, 2009**

(30) **Foreign Application Priority Data**

Mar. 23, 2009 (EM) 001110407-0001
